KELLY DRIVE BUSHING

Charles S. Shaffer, Odessa, Tex.

Application August 27, 1947, Serial No. 770,824

2 Claims. (Cl. 255—23)

1

This invention relates to well drilling equipment, and more particularly to well drilling equipment including the well known Kelly bushing or drive bushing designed for use in connection with rotary tables of well drilling rigs.

An important object of the invention is to provide a bushing wherein roller bearings are held within a body portion including a cage, to contact with the square stem or kelly of the drilling string, whereby lateral movement of the stem or kelly will be prevented, thereby reducing wear to a minimum.

Another object of the invention is to supply adjustable bearings mounted within the body portion, the bearings providing a support for the rollers in which the stem or kelly is boxed, thereby permitting the use of rollers of a predetermined size, with various sized stems or kellys.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawing:

Figure 1 is an elevational view of a bushing constructed in accordance with the invention.

Figure 2 is a sectional view taken on line 2—2 of Figure 1.

Referring to the drawing in detail, the bushing forming the subject matter of the present invention comprises the body portion indicated generally by the reference character 5, the body portion having the reduced lower end portion 6 square in cross section and designed to fit within the usual square opening of a rotary table in which bushings of this type are mounted to move with the table.

The body portion includes a boxing or cage embodying corner plates 7 rising from the plate 8, to which the corner plates are rigidly secured.

Each corner plate embodies sections disposed at right angles with respect to each other, the open sides of the corner plates being disposed outwardly.

The inner surfaces of the corner plates are formed with pairs of inclined grooves 9 which are inclined inwardly from the upper ends of the corner plates, as clearly shown by the drawing.

The grooves 9 accommodate the ribs 10 which are disposed along the rear inclined edges of the segments 11, which segments are provided with inner edges parallel with the stem or kelly 12. Thus it will be seen that due to this construction, the segments 11 may be readily removed from the grooves in which they are shown in Figure 2 of the drawing, and inserted in the inner grooves, should it be desired to use the bushing with a smaller kelly.

Reference character 13 indicates horizontally

2

aligned rollers the pintles 14 of which rest against the inner edges of the segments as clearly shown.

The arrangement of rollers 13 is such that they provide a boxing for the stem or kelly 12 to maintain the same in vertical position at all times, insuring against lateral movement of the stem or kelly during operation, which usually results in undue wear on the kelly to render the same inoperative.

It might be further stated that the grooves formed in the corner plates, are so arranged that when the rollers are positioned against the segments, the space between the rollers will form a boxing in which the stem or kelly moves in a true vertical movement.

Having thus described the invention, what is claimed is:

1. The combination with a Kelly bar, of a Kelly bar bushing comprising a base plate having an extension adapted to be fitted in an opening of a rotary drill table, corner plates rising from the base plate, each corner plate having pairs of spaced longitudinal grooves formed in the inner surfaces thereof, said grooves being inclined inwardly towards the lower ends of the corner plates, elongated bearing segments fitted against the inner surfaces of the corner plates, longitudinal ribs extending laterally from the outer longitudinal edges of the segments said ribs being substantially narrow and fitted in certain of the grooves, securing the segments to the corner plates, and rollers supported by the segments, the rollers operating against the Kelly bar operating through the bushing.
2. The combination with a Kelly bar, of a Kelly bar bushing comprising a base plate having an extension adapted to be fitted in an opening of a rotary drill table, corner plates rising from the base plate, each corner plate having pairs of spaced outer and inner longitudinal grooves formed in the inner surfaces thereof, elongated bearing segments, roller bearings mounted on the inner edges of the segments for engagement with a kelly operating therethrough, longitudinally disposed outwardly extended ribs formed on the outer longitudinal edges of the segments, adapted to be fitted in the grooves of the corner plates, removably securing the bearing segments within the corner plates.

CHARLES S. SHAFFER.
